FRED N. LA CHAPELLE, OF BEVERLY, MASSACHUSETTS, ASSIGNOR TO UNITED SHOE MACHINERY CORPORATION, OF PATERSON, NEW JERSEY, A CORPORATION OF NEW JERSEY.

METHOD OF MAKING SHOES.

1,412,082.

Specification of Letters Patent. Patented Apr. 11, 1922.

Application filed June 20, 1919. Serial No. 305,484.

To all whom it may concern:

Be it known that I, FRED N. LA CHAPELLE, a citizen of the United States, residing at Beverly, in the county of Essex and State 5 of Massachusetts, have invented certain Improvements in Methods of Making Shoes, of which the following description, in connection with the accompanying drawings, is a specification, like reference characters on the 10 drawings indicating like parts in the several figures.

This invention relates to methods of making shoes and particularly to methods of making shoes in which the margin of the 15 upper is turned outwardly and attached to the margin of the sole, shoes of this type being generally known as stitchdown shoes.

It is, of course, a prime requisite to good 20 shoemaking that the shoe upper be properly lasted, that is, that the various portions of the upper about the periphery of the shoe, particularly along the sides and around the toe, be tensioned in a direction perpendicular to the last bottom and held temporarily 25 against the sides of the last, including the portion of the sides adjacent to the sole edge, before they are permanently attached to the sole.

In the manufacture of stitchdown shoes 30 by a known method, the margin of the upper is temporarily fastened to the edge face of the projecting sole by tacks. When this is done, however, no substantial tension can be applied to the upper and maintained since 35 the holding power of the tacks, when driven into the leather of the sole, is slight and the upper, since it is bridged across the angle between the side of the last and the projecting margin of the sole, can not be brought 40 into final lasted position when thus temporarily secured.

An object of this invention is to provide 45 a machine for lasting stitchdown shoe uppers by which an upper may be pulled and wiped into lasted position in the highly efficient manner heretofore practiced only in lasting welt and McKay shoes and may be temporarily secured to the last bottom.

In one of its broader aspects the present 50 invention consists in lasting an upper over a last and temporarily securing the margin of the upper directly to the last bottom, the sides of the upper being thereby brought against the sides of the last into finally lasted 55 position. As herein exemplified, the upper is then further secured in lasted position

along the line at which the margin of the upper is to be turned outwardly to form the sole attaching flange, after which the first and temporary fastenings are withdrawn 60 and the flange of the upper is turned outwardly, a sole being then applied and secured to the outturned margin of the upper.

In another aspect the invention consists in providing on the last itself an angle into 65 which the upper may be lasted as, for example, by providing a plate on the last bottom which projects slightly beyond the side face of the last. This aspect of the invention is especially applicable at the toe of the 70 shoe where the upper is wiped against the end and sides of the toe and forced into the angle between the side of the last and the projecting plate. This causes the portion of the upper margin beyond the plate to flare 75 outwardly and the upper may be secured in the angle in finally lasted position by a binding wire located in the angle of the upper and secured at its ends, for example, to the forward pair of temporary tacks employed to secure the side portion of the upper margin to the last bottom. The lasting of the toe is effected, of course, before the sole is applied as described above.

In practice a last is provided which has 85 upon its bottom an iron plate which preferably covers the entire surface of the last bottom and at the toe end of the last projects slightly beyond the edge of the last. Along the sides of the last bottom openings are 90 provided in the plate in which tacks may be driven into the wood of the last. The plate is also provided at certain points along the sides of the last with slots which are open at the edge of the last and in which slots there 95 are hooks, the ends of which are below the general surface of the last bottom. An upper prepared as usual is placed over the last, successive portions of the upper tensioned to it and laid over the last bottom to which they 100 are secured by tacks driven through the openings in the plate into the wood of the last. At the toe of the last the upper may be tensioned and wiped as usual in a direction 105 toward the last bottom and formed into the angle between the side of the last and the slightly projecting margin of the plate. Around the toe the upper may be held in lasted position by a binding wire applied around the toe in the angle formed in the 110 upper between the side of the last and the projecting plate, the wire being anchored to

the side by the lasting tacks which are adjacent to the toe end of the shoe. Obviously, the lasting of the shoe may be performed by hand or by lasting machines of known type 5 such as bed lasting machines. After the upper is lasted it is secured at the line along which it is to be bent outwardly by passing a cord or thread through the upper at points opposite to the hooks above mentioned and 10 hooking the thread over the hooks. About the toe of the shoe the thread is carried around the shoe toe in the same location as the toe binding wire which is subsequently removed as are also the lasting tacks which 15 were driven into the wood of the last. The upper is now turned outwardly at right angles to the sides of the last and its margin cemented. A sole is now applied to the shoe and secured to the cemented margin of the 20 upper, after which the sole may be secured to the upper and a welt and second sole applied, if desired, in the usual manner. Preferably at the heel end of the shoe a piece of leather the shape of a heel-seat is applied to 25 the iron plate and the upper is turned in and permanently secured to the piece of leather.

In the drawings,—

Fig. 1 is a view of the bottom of a shoe the upper of which has been lasted in accordance with the present invention;

Fig. 1^a is a sectional detail of the toe of the shoe shown in Fig. 1;

Fig. 2 is a perspective view, partly in section, showing the manner of securing the upper by a retaining thread to permit the lasting tacks to be withdrawn;

Fig. 3 is a similar view showing the manner of securing the upper temporarily by lasting tacks;

Fig. 4 shows the lasting tacks removed and the upper turned outwardly and ready to receive the sole; and

Fig. 5 is a perspective detail, partly in section, showing the outturned upper secured to the sole.

In Fig. 1 the numeral 2 indicates a bottom plate of metal secured to the bottom of the last by screws 4. This plate 2 preferably covers the entire bottom of the last and has 50 its edge flush with the side of the last except about the toe portion where the margin of the plate projects slightly beyond the edge of the last, the projection being, for example, $\frac{1}{2}$ of an inch. The heel seat portion of 55 the plate 2 is covered by a piece of leather or other suitable material 6 and the margin of the upper is lasted over upon the piece 6 in the usual manner and secured by tacks 8 which are clenched upon the plate 2.

60 Along the sides of the last the plate 2 is provided with holes 10 (Fig. 4), exposing the wood of the last, through which tacks 12 are driven temporarily to secure the margin of the upper over the last bottom under tension in lasted position.

At the toe end of the last the upper is preferably lasted by pressing the upper against the last, and wiping it upwardly toward and against the projecting portion of the plate 2. This may be done by the 70 wipers of a bed lasting machine. The upper at the toe may then be secured in lasted position by a binding wire 14 secured at its ends to the foremost side lasting tacks 12. Since the binding wire 14 is seated in the 75 angle between the side of the last and the projecting portion of the plate 2 it causes the upper about the toe to flare outwardly (Fig. 1^a). To enable the upper at the sides of the shoe to be bent outwardly, it is held 80 against the side of the last adjacent to the edge of the plate 2 by a cord, thread, or other filament 13 arranged along the line where the outward bend should be located, the cord being secured to the last at salient 85 points. This may conveniently be effected by employing a needle having an eye in its point through which the thread is passed. At various points along the sides of the last recesses 16, opening at the edge of the last, 90 are provided and in each recess is a hook 18. The threaded needle is passed through the upper and open end of the recess 16 and the cord 13 hooked over the hook 18 (Fig. 2). The needle is then withdrawn and carried along the sides of the last to the next recess where the operation is repeated. When one side of the last has been thus treated the cord may conveniently be carried around the toe, and the upper at the 100 other side of the last secured in place by passing the cord through the upper and over the hooks 18 along that side of the shoe. The friction of the thread over the hooks is sufficient to hold the thread without otherwise securing it.

Next the lasting tacks 12 are withdrawn and the upper at the sides turned outwardly, cuts 20 being made at the juncture of the sides with the heel-seat to permit turning 110 out the portions of upper adjacent to the heel-seat portion which has already been lasted inwardly. A sole 22 is now secured to the shoe or last, for instance, by cementing the outwardly turned margin of the 115 upper and applying the sole to the last bottom. After the cement has set the cord 13 may be removed and the projecting margin of the sole and out-turned margin of the upper sewed together as at 24 by an 120 outsole stitching machine.

For some purposes the shoe is now complete except for certain trimming and finishing operations, as will be apparent, but if desired a second sole may be secured in 125 a similar manner and a welt applied to the top face of the outturned upper, as is usual in this type of shoe. If desired, the second sole and welt may be applied before any stitching is done and the welt, upper and 130

both soles secured together at the same time by a single stitching operation. Of course the welt and a single heavy sole may be employed if a lighter shoe is desired.

5 Having thus described my invention, what I claim as new and desire to secure by Letters Patent of the United States is:

1. That improvement in methods of making stitchdown shoes which consists in assembling an upper upon a last, tensioning the upper about the sides of the last and temporarily securing the upper in contact with the last and under tension, additionally holding the upper to the last, releasing the upper from the first-named temporary securing means, applying a sole to the last bottom, and thereafter completing the manufacture of the shoe.
- 10 2. That improvement in making stitchdown shoes which consists in tensioning and lasting over the margin of the sides of the upper against the bottom of the last, temporarily securing the upper in lasted position, holding the upper to the last along the line at which it is to be bent outwardly, releasing the temporary securing means, bending outwardly the margin of the upper, and then securing the out-turned upper to the margin of a sole.
- 15 3. That improvement in making stitchdown shoes which consists in providing a last with a bottom plate which extends slightly beyond the last about the toe, wiping the upper about the toe against the last and into the angle between the side of the last and the projecting plate, securing the upper in the angle by a binding wire, and then securing a sole to the outwardly disposed margin of the upper about the toe.
- 20 4. That improvement in making stitchdown shoes which consists in assembling an upper upon a last, lasting over the margin of the upper and securing it under tension in contact with the last bottom, holding the upper to the last along the line at which it is to be turned outwardly, releasing the upper where first secured, turning the upper outwardly along said line, applying a sole to the last bottom, and securing the out-turned upper to the margin of the sole.
- 25 5. That improvement in making stitchdown shoes which consists in tensioning and lasting over the margin of the sides of the upper against the bottom of the last, temporarily securing the upper in lasted position to the last bottom, applying a thread to hold the upper to the last along the line at which it is to be bent outwardly, releasing the said temporary securing means, bending outwardly the margin of the upper, and then securing the out-turned upper to the margin of a sole.
- 30 6. That improvement in making stitchdown shoes which consists in providing a last with a bottom plate which extends slightly beyond the last about the toe, wiping the upper about the toe against the last and into the angle between the side of the last and the projecting plate to cause the upper at the toe to project outwardly, and then securing a sole to the outwardly disposed margin of the upper.
- 35 7. That improvement in making stitchdown shoes which consists in assembling an upper upon a last having no insole thereon, lasting over the sides of the upper and tacking them under tension to the last bottom, holding the upper to the last along the line at which it is to be turned outwardly, withdrawing the tacks, turning the upper outwardly along said line, applying a sole to the last bottom, and securing the out-turned upper to the margin of the sole.
- 40 8. That improvement in methods of making shoes which consists in lasting an upper over the bottom of a last, securing the upper temporarily in lasted position, passing a thread loop at widely spaced points through the upper in a direction substantially in the plane of the last bottom, securing the loop to the last, repeating the operation about the periphery of the shoe, tightening the thread to hold the upper against the last, releasing the temporarily secured upper margin and turning it outwardly, securing a sole to the out-turned margin, and removing the thread.
- 45 9. That improvement in methods of making shoes which consists in providing a last with a bottom plate that projects slightly beyond the edge of the last at the toe, lasting the upper over the last bottom upon the plate, fastening a toe binding wire about the toe in the angle between the side of the last and the projection of the plate, turning the overlasted maring of upper outwardly, and securing a sole to the out-turned margin.
- 50 10. That improvement in methods of making shoes which consists in providing a last with a bottom plate that projects slightly beyond the edge of the last at the toe, conforming the upper to the last about the toe portion, fastening the upper in place by a filament passing around the toe, thereby turning the edge of the upper outwardly, and fastening a sole to the out-turned upper.
- 55 11. That improvement in methods of making shoes which consists in conforming an upper to its last, passing a loop of thread through the upper at the juncture of the side of the last with the last bottom, securing the loop to the last, similarly passing through and securing other loops of the same thread, tightening the thread to hold the upper to the last, turning outwardly the margin of the upper which extends beyond the thread, and securing a sole to the out-turned margin.
- 60 12. In testimony whereof I have signed my name to this specification.

slightly beyond the last about the toe, wiping the upper about the toe against the last and into the angle between the side of the last and the projecting plate to cause the upper at the toe to project outwardly, and then securing a sole to the outwardly disposed margin of the upper.

70 7. That improvement in making stitchdown shoes which consists in assembling an upper upon a last having no insole thereon, lasting over the sides of the upper and tacking them under tension to the last bottom, holding the upper to the last along the line at which it is to be turned outwardly, withdrawing the tacks, turning the upper outwardly along said line, applying a sole to the last bottom, and securing the out-turned upper to the margin of the sole.

75 8. That improvement in methods of making shoes which consists in lasting an upper over the bottom of a last, securing the upper temporarily in lasted position, passing a thread loop at widely spaced points through the upper in a direction substantially in the plane of the last bottom, securing the loop to the last, repeating the operation about the periphery of the shoe, tightening the thread to hold the upper against the last, releasing the temporarily secured upper margin and turning it outwardly, securing a sole to the out-turned margin, and removing the thread.

80 9. That improvement in methods of making shoes which consists in providing a last with a bottom plate that projects slightly beyond the edge of the last at the toe, lasting the upper over the last bottom upon the plate, fastening a toe binding wire about the toe in the angle between the side of the last and the projection of the plate, turning the overlasted maring of upper outwardly, and securing a sole to the out-turned margin.

85 10. That improvement in methods of making shoes which consists in providing a last with a bottom plate that projects slightly beyond the edge of the last at the toe, conforming the upper to the last about the toe portion, fastening the upper in place by a filament passing around the toe, thereby turning the edge of the upper outwardly, and fastening a sole to the out-turned upper.

90 11. That improvement in methods of making shoes which consists in conforming an upper to its last, passing a loop of thread through the upper at the juncture of the side of the last with the last bottom, securing the loop to the last, similarly passing through and securing other loops of the same thread, tightening the thread to hold the upper to the last, turning outwardly the margin of the upper which extends beyond the thread, and securing a sole to the out-turned margin.

95 12. In testimony whereof I have signed my name to this specification.
